Primary Examiner—Lucy Lieberman

(57) **CLAIM**

The ornamental design for a watch, as shown and described.

DESCRIPTION

FIG. 1 is a front perspective view of a watch showing our new
design;

FIG. 2 is a front elevation thereof;

FIG. 3 is a rear elevation thereof;

FIG. 4 is a right side elevation thereof shown with the watch
in an inverted position;

FIG. 5 is a left side elevation of the watch; and,

FIG. 6 is a bottom view of the watch.

1 Claim, 4 Drawing Sheets

FIG. 3

FIG. 2

FIG. 5

FIG. 4

FIG. 6
